UNITED STATES PATENT OFFICE

ARTHUR F. VAN DYCK, OF YONKERS, NEW YORK, ASSIGNOR TO RADIO CORPORATION OF AMERICA, A CORPORATION OF DELAWARE

RADIO RECEIVING SYSTEM

Application filed September 15, 1926. Serial No. 135,497.

My invention relates to radio receiving systems and particularly to receiving systems embodying an electro-static loud speaker device.

5 An object of my invention is to provide a radio responsive system adapted to cooperate with an electro-static loud speaker device.

Another object of my invention is to provide a radio responsive device adapted to 10 change signal modulated radio frequency energy from signal frequency to optimum frequency for an electro-static loud speaker device.

The usual radio receiving systems operate 15 at a disadvantage because of the fact that rectification or detection of the received signals is necessary before the usual signal receiver can be operated. Such detection is accompanied by an undesirable distortion 20 which destroys to some extent the true character of the signals. I have found that the so-called electro-static loud speaker which has been known in a rudimentary form in the prior art, but has heretofore been operated 25 only by audio frequency currents such as those produced by a radio detector, will also respond at an audible frequency, to radio frequencies which are modulated at an audio frequency, and reproduce the sound corresponding to the modulation frequency.

I have also found that for most practicable operation of an electro-static loud speaker that it must be supplied with energy in certain preferred forms and conditions, and 35 that the loud speaker should desirably be combined with a radio responsive system especially adapted to provide energy in the proper form for it.

The electro-static loud speaker consists 40 essentially of an electrical condenser in which provision is made for vibration of a condenser plate, under the influence of the electro-static attraction of an electric charge upon the plates, the vibration of the plate 45 being caused to produce air vibrations, for sound. The electric charge may be caused to vary directly at an audible frequency to which the vibratory plate can respond, or the energy may be impressed in the form of 50 modulated radio frequency energy, in which

case the vibratory plate is unable to respond to the radio frequency vibrations but can respond to the modulations impressed upon the radio frequency vibrations. This is because the attraction between charged plates does not vary linearly with charge, so that a component of force varying at modulation frequency is produced by modulated radio frequency. The latter system is preferable in a radio receiving system for reasons herein disclosed. When so used the magnitude of the response of the loud speaker, in producing sound corresponding to the audio frequency modulations, is determined by the amplitude of the radio oscillations impressed.

55 For instance, the electro-static loud speaker may be connected across a tuning element in an antenna circuit at a point of maximum potential. This connection, however, is unsatisfactory because the energy available in the antenna circuit is small, lacking amplification. A better response from the electro-static loud speaker may be obtained by 60 interposing a typical triode amplifier system between the antenna system and the loud speaker, thereby increasing the amplitude of the oscillations.

65 A superior response of the electro-static loud speaker may sometimes be secured by reducing the radio frequency, as well as increasing its amplitude, by the interposition not only of a typical triode amplifier system but also of a heterodyning system to reduce the radio frequency oscillations to a lower 70 radio frequency to which the loud speaker will under certain circumstances respond more effectively. Also the difficulties of securing high degrees of amplification are lessened.

75 A further gain in response of the loud speaker may be obtained from an amplifying and heterodyning system, by reflexing the lower radio frequency through the triodes provided for the amplification of the higher radio frequency.

80 By this construction, energy in a proper form is supplied to an electro-static loud speaker device to obtain a maximum sound volume therefrom. The energy is further obtained without the intervention of a de- 85

5 tector or rectifier device, thereby avoiding the distortion which otherwise necessarily occurs in a detector system. I am thus enabled to operate a loud speaker directly at radio frequency for the production of signals having adequate sound volume and maximum clarity and faithfulness of reproduction.

10 Other objects and structural details of my invention will be apparent from the following description when read in connection with the accompanying drawing, wherein:

15 Figure 1 is a diagrammatic representation of circuits and apparatus of my invention.

20 Figure 2 is a diagrammatic representation of a superior embodiment of my invention.

25 Figure 3 is a diagrammatic representation of circuits and apparatus representing a preferred embodiment of my invention.

30 Referring to Figure 1, I provide an antenna system 1, a radio frequency amplifier 2, having a tuned input circuit 3 and a tuned output circuit 4, and an electro-static loud speaker device 5. By this device the incoming signal frequency is received by the antenna 1, transferred to the input circuit 3, amplified by the amplifier 2 and fed to the output circuit 4. Circuit 4 being tuned to the incoming radio frequency of the signal, maximum oscillation voltage at the modulated signal frequency is impressed upon the loud speaker 5 and a superior sound response is obtained than would be obtained from the device if it were connected directly to the antenna circuit.

35 Referring to Figure 2 I provide as before an antenna system 1, and a radio frequency amplifier 2 having a tuned input circuit 3. I further provide a heterodyning means 6 connected thereto and supplied with steady oscillatory energy at a frequency differing from that of the signal frequency by an amount equal to another radio frequency, from a generator 7. I provide an output circuit 8 connected to the heterodyning device and tuned to the heterodyne beat frequency. An electro-static loud speaker 5 is connected to the tuned circuit 8. By this means I supply to the electro-static loud speaker device 50 a substantial amplitude of modulated radio frequency energy at an optimum frequency, the frequency of the source 7 being chosen to differ from the incoming signal frequency by an amount above the highest audible frequency. By this means the electro-static loud speaker is supplied with a substantial amount of modulated radio frequency energy at an optimum frequency.

45 Referring to Figure 3 I show a system 60 whereby maximum utilization of the triodes of an amplifier is made. As before, I provide an antenna system 1 coupled to the tuned input circuit 3 of a radio frequency amplifier 2. The amplifier 2 may consist of a triode 9 having an output transformer 11,

55 associated with a second triode 12 having a second output transformer 14, in turn associated with a heterodyning device 6. The heterodyning device 6 may desirably consist of a triode 15 and a feed-back transformer coupling device 16. The output circuit of the triode 15 is connected to a tuned reflexing transformer device 17 which is connected between the tuned input circuit 3 and the triode 9. Means are provided in the transformer 11 for the transferring of energy at the original signal frequency and also at the heterodyne frequency. A second output transformer 18 is provided in the output circuit of the triode 12. The transformer 18 has its secondary circuit tuned to the beat frequency and connected to the electro-static loud speaker device 5.

60 By the embodiment of my invention shown in Figure 3 signals are received upon the antenna system 1, transferred to the input circuit 3, amplified by the triode 9, transferred by the coupling transformer 11 to the triode 12, and amplified therein. Signals, still at the original frequency, are transferred from the triode 12 by the coupling transformer 14 to the triode 15. The triode 15 is caused to generate oscillations by the feed-back transformer 16, at a proper frequency for the production of a beat frequency. The signal modulations at the beat frequency are transferred through the reflexing transformer 17 to the grid circuit of the triode 9, amplified therein, independently of the signals at the original higher signal frequency, transferred therefrom through the transformer 11, to the triode 12, again amplified therein, independently of the signals at the original frequency, and transferred through the output transformer to the electro-static loud speaker device 5. The secondary circuit of the output transformer 18 is tuned to the beat frequency and an optimum amount of energy at an optimum amplitude is thus impressed upon the electro-static loud speaker 5.

65 It is to be noted that the operation of rectification or detection does not occur at any point in the transfer of the signals to the loud speaker device and that, therefore, distortion necessarily inherent in all detection processes is avoided.

70 While I have shown but three embodiments of my invention in the foregoing drawings and descriptions it is capable of various modifications therefrom without departing from the spirit thereof, and it is desired therefore that only such limitations shall be imposed thereon as are required by the prior art or indicated by the appended claim.

75 I claim as my invention:

80 Apparatus for reproducing sound from a modulated radio frequency signal comprising a circuit energized by said signal, a local source of energy, amplifying and detecting means for obtaining an amplified superaudi-

ble beat frequency from said signal and the energy from said local source, a tuned circuit connected to the output of said amplifying and detecting means for obtaining a resonance potential rise, said tuned circuit consisting of an inductive reactance element and a capacitive reactance element connected in parallel, and an electrostatic loud-speaker connected across the terminals of one of the reactance elements whereby the maximum potential obtained by said resonance potential rise is applied across the electrostatic loud-speaker terminals and the electrostatic loud-speaker functions as a detector to reproduce sound from said superaudible beat frequency.
